UNITED STATES PATENT OFFICE.

FRANK M. ASHLEY, OF NEW YORK, N. Y.

INKSTAND.

1,202,016.

Specification of Letters Patent. Patented Oct. 24, 1916.

Application filed November 22, 1912. Serial No. 732,933.

To all whom it may concern:

Be it known that I, FRANK M. ASHLEY, a citizen of the United States, and a resident of New York, borough of Brooklyn, in the 5 county of Kings and State of New York, have invented certain new and useful Improvements in Inkstands, of which the following is a specification.

This invention relates to inkstands, more 10 particularly to the two part type of stand having a rotary cover.

The principal object of the present invention is to provide a stand of the character above described which is simple in construction and easy to manufacture.

A further object is to provide a stand in which the cover is substantially flush with the top of the base.

Another object is to provide a stand with 20 a dip opening which may be quickly closed by simple movement of the cover, the latter being always held in position closely adjacent to the dip opening.

Various other features of novelty and the 25 advantages accruing therefrom will appear from the detailed description and will be particularly pointed out in the claims.

In the accompanying drawings, Figure 1 is a plan view of the inkstand with the 30 cover rotated to position to expose the dip opening. Fig. 2 is a section along line 2—2 of Fig. 1. Fig. 3 is a plan view of a modified form of construction. Fig. 4 is a section taken along line 4—4 of Fig. 3 as it 35 would appear with the dip 3^a closed by the extension 7^a of the cover.

Referring to the embodiment of my invention illustrated in Figs. 1 and 2, the base 1 consists preferably of a low slab of glass 40 having a main reservoir 2 formed therein and a dip chamber 3 extending beyond the reservoir. Adjacent to the reservoir and dip opening, the base is reduced to form a substantially annular recess 4 and an arc 45 shaped extension thereof 5 located adjacent to the dip chamber. The cover consists of a substantially flat, circular member 6 having an arcuate projection 7 extending therefrom. The circular portion 6 is adapted to 50 seat in the annular recess 4, while the arcuate portion 7 is adapted to work in the arc shaped recess 5 adjacent to the dip chamber. The recess 5 is of sufficient length to allow the arcuate projection 7 to be swung 55 therein so as to uncover the dip opening

when swung to one side and to completely cover the same when swung to the other side.

In the construction illustrated in Figs. 3 and 4, the base 1^a has the reservoir 2^a 60 and the dip chamber 3^a formed therein, and is provided also with an arc shaped rib 4^a adjacent to the mouth of the well. The cover consists of a circular portion 6^a and an arcuate extension 7^a which extends outwardly therefrom in position to cover and uncover the dip chamber 3^a. Shoulders 8 and 9, forming the ends of the arc shaped rib 4^a, limit the rotary movement of the cover in opening and closing the dip chamber. The line 10 indicates the position of the edge of the extension 7^a when the dip is closed thereby.

It will be seen that I have provided an inkstand which is very simple in construction and is easy to manufacture. The cover is entirely flat and offers no thin projections or ridges which may become broken. The movement of the cover is also limited so as to be always in position wherein it 80 may be readily and quickly closed. By the disposition of the cover in the recess, the cover is substantially flush with the top of the base and will not easily be knocked off therefrom.

Having thus described my invention, I claim as new:

1. A two part stand consisting of a base having a reservoir therein, a substantially circular socket formed immediately about the top edge of the reservoir, an enlargement of the socket extending therefrom, an ink dip communicating with the reservoir and disposed within the bounds of the enlargement of the socket, a rotary solid cover 90 having a substantially circular portion seating in said socket and engaging the circumferential wall thereof, and a projection extending beyond the socket for covering the ink dip, said projection being limited 95 in its rotary movement by the walls of said enlargement.

2. An inkstand comprising a base having a reservoir and an ink dip extending exteriorly thereof, there being a countersunk substantially annular recess in the base adjacent to the reservoir, said recess having an arc shaped extension within the bounds of which the dip is located, a cover seating 105 in said annular recess and having a projec- 110

tion extending into said arc shaped extension, the latter being substantially larger than either the dip or projection.

3. An inkstand comprising a base having a reservoir therein, a socket formed about the upper edge of said reservoir, the walls of said socket being substantially circular, there being a break therein of substantial length, a rotary cover for the reservoir located within the socket, the outer edge thereof being substantially flush with the upper surface of the wall of the socket, an ink dip communicating with the reservoir and located without the socket adjacent the

break in the wall thereof, and a projection 15 extending from said cover and through said break and adapted to cover and uncover said ink dip when the cover is rotated, the break being longer than the width of the projection and limiting the rotation of said 20 cover.

Signed at New York, in the county of New York, and State of New York, this 19th day of November A. D. 1912.

FRANK M. ASHLEY.
